UNITED STATES PATENT OFFICE.

WILLIAM D. MARKS, OF PHILADELPHIA, PENNSYLVANIA, ASSIGNOR TO THE AMERICAN ELECTRIC METER COMPANY, OF SAME PLACE.

DESIGN FOR A METER-CASE.

SPECIFICATION forming part of Design No. 28,309, dated February 22, 1898.

Application filed November 27, 1896. Serial No. 613,698. Term of patent 14 years.

To all whom it may concern:

Be it known that I, WILLIAM D. MARKS, a citizen of the United States, residing at Philadelphia, in the county of Philadelphia and State of Pennsylvania, have invented and produced a new and original Design for a Meter-Case, of which the following is a specification.

The accompanying drawings illustrate my design for an electric-meter case, Figure 1 being a perspective view, and Fig. 2 a top view.

The leading features are a meter-case A, rectangular in cross-section, having rounded

corners and provided at the sides with inclined projections a, each of the form of a truncated cone.

What I claim is—

The design for an electric-meter case herein shown and described.

This specification signed and witnessed this 24th day of November, 1896.

WM. D. MARKS.
